CLAIM

The ornamental design for an electronic display device, as shown and described.

DESCRIPTION

FIG. 1 is a top, front, left perspective view of an electronic display device.

FIG. 2 is bottom, rear, left perspective view thereof.

FIG. 3 is a front view thereof.

FIG. 4 is a rear view thereof.

FIG. 5 is a top view thereof.

FIG. 6 is a bottom view thereof.

FIG. 7 is a left side view thereof.

FIG. 8 is a right side view thereof; and,

FIG. 9 is an enlarged view of the detail area '9' as seen in FIG. 1.

The broken lines depict portions of the electronic display device which form no part of the claimed design. The set of broken lines in FIG. 1 indicated as detail area '9' is included for annotative purposes and forms no part of the claimed design.

1 Claim, 7 Drawing Sheets(56)
